Fig. 5

Fig. 6

FIG. 1 is a perspective view of a safety cotton swab showing my new design;

FIG. 2 is a side elevational view thereof;

FIG. 3 is an end elevational view thereof;

FIG. 4 is a top plan view thereof;

FIG. 5 is a perspective view of a second modified embodiment of the swab illustrated in FIG. 1; and

FIG. 6 is a perspective view of a third modified embodiment of the swab illustrated in FIG. 1.

I claim:

The ornamental design for a safety cotton swab, as shown and described.
